United States Patent Office

Des. 188,600
Patented Aug. 16, 1960

188,600

ELECTRIC SHAVER

Robert O. Ernest, Oak Park, Ill., assignor to Sunbeam Corporation, Chicago, Ill., a corporation of Illinois

Filed Sept. 4, 1959, Ser. No. 57,427

Term of patent 14 years

(Cl. D22—3)

Fig. 1 is a front perspective view of a shaver embodying my new design;

Fig. 2 is a front elevational view thereof, the side opposite being similar in appearance;

Fig. 3 is a side elevational view thereof, the side opposite being similar in appearance; and

Fig. 4 is a top plan view thereof.

The dominant features of the design reside in the portions shown in full lines.

I claim:

The ornamental design for an electric shaver, as shown and described.
